UNITED STATES PATENT OFFICE.

ALBERT HAYES, OF NEW YORK, N. Y., ASSIGNOR, BY MESNE ASSIGNMENTS, TO
GEORGE F. MCKAY, OF NEW YORK, N. Y.

CHARGE-FORMING MEANS FOR INTERNAL-COMBUSTION ENGINES.

1,360,742.

Specification of Letters Patent.

Patented Nov. 30, 1920.

Application filed February 2, 1920. Serial No. 355,540.

To all whom it may concern:

Be it known that I, ALBERT HAYES, a citizen of the United States, residing at New York, in the county of New York, State of New York, have invented certain new and useful Improvements in Charge-Forming Means for Internal-Combustion Engines, of which the following is a description, reference being had to the accompanying drawings, forming a part hereof.

My invention relates to internal combustion engines and particularly to internal combustion engines adapted to use fuel oil, that is oil heavier than gasolene, as the basis of the explosive charge and to the type of such engines in which the fuel oil is introduced into the combustion space to form the explosive charge therein by mixing with air compressed therein, and my invention has for its object to provide means by which the fuel oil will be so heated and so forced into the compression space and so scattered throughout the body of compressed air that it will form with the compressed air an intimate mixture which will instantly ignite without special igniting means.

A further object of the invention is to provide means for heating the oil and forming the explosive mixture which will be effective to form the mixture and cause it to ignite without other igniting means than the heat of compression not only after the engine has been heated up but also on the initial stroke, in other words to provide means which will be effective to start an internal combustion engine using fuel oil as well as to operate it after it is once started, with the fuel oil only and without the use of light hydrocarbon for priming and without special igniting means.

A further object of my invention is to provide means for scattering or disseminating the fuel oil through the compressed air in the compression space so as to form an effective explosive mixture and to cause the charge thus formed to ignite, without the use of mechanical force.

A further object of my invention is to provide means by which the oil chamber or receptacle in which the charge of oil is heated will be thoroughly cleansed of oil or oil products as each charge is formed so that there will be no possibility of deposit of carbon or other matter in such chamber or receptacle.

A further object of my invention is to provide simple and inexpensive means by which the heat of the air compressed in the compression space will be effectively utilized to heat the oil used and simple, inexpensive and effective means for causing the heated oil to be impelled or ejected into the compressed air in the compression space so quickly and forcibly that it will form an explosive mixture and will bring this explosive mixture to the heat necessary for ignition.

A further object of my invention is to provide means whereby fuel oil may be introduced into a chamber or receptacle to be heated therein, means whereby water may be introduced into such chamber or receptacle to be converted into superheated steam by the heat of the oil and means by which the heated oil is expelled from the chamber or receptacle by the steam so generated from the water.

A further object of my invention is to provide means by which a portion of the gases of explosion may be retained after the explosion of a charge to heat the oil in the oil chamber or receptacle and to maintain a flame to ignite a subsequent charge.

I am, of course, aware that in the Diesel type of internal combustion engine fuel oil is forced or sprayed into the cylinder when the air therein has been compressed to such a degree that its temperature is above that at which a mixture of oil and air will ignite, the heat of compression being depended on to effect the ignition. For operation of a Diesel engine very high compression is required and considerable mechanical power is required to force or spray the oil into the body of highly compressed air in the cylinder. I am also aware that it has been proposed to heat a charge of oil by the heat of compression and, by forcing it into the compression space, form an explosive mixture which, when the engine has been heated up, will ignite, but in all such engines difficulty has been found in starting and it has been found necessary to start by priming with gasolene or other light hydrocarbon or to use special means such as electric heating coils and special igniting means or to raise the degree of compression to the point at which the temperature produced by the compression is sufficiently high to ignite.

By the use of my invention the engine

may be started without preheating, with the fuel oil which is used for operation, without the addition of light hydrocarbon, without special heating means and without any 5 heating means other than the means herein described for producing ignition at the comparatively low compression used.

With the above described objects and other objects hereinafter described in view, 10 my invention consists in the construction and combination of elements hereinafter described and claimed.

Referring to the drawings,

Figure 1 is a longitudinal central vertical 15 sectional view of a portion of the cylinder of an internal combustion engine provided with charge forming and igniting devices embodying my invention.

Fig. 2 is a front elevation of the charge 20 forming device, and

Fig. 3 is a front elevation of the valve and 25 valve rod of the charge forming device.

Fig. 4 is a central sectional view of a portion of the charge forming device on an enlarged scale.

In the drawings 1 indicates the cylinder of an internal combustion engine here shown as horizontally arranged but which may be vertical if desired. 2 indicates the water 30 jacket of the cylinder. 3 indicates the piston provided with piston rings 4. The piston is preferably made to have a grinding fit in the cylinder so as to avoid leakage and to make it possible to get relatively high 35 compression. 5 indicates the cylinder head and 6 indicates one of the two inwardly opening valves used respectively for controlling the inlet of air and the exhaust as is usual in four cycle internal combustion 40 engines. 7 indicates the outer wall of the valve chamber secured to or formed with the cylinder head and 8 indicates the spring carried by the valve rod of each of the inwardly opening valves and acting to hold its 45 valve normally closed. These valve rods are arranged to be operated to open their valves at the proper time by any usual means employed for this purpose in such engines.

50 9 indicates an opening formed in the cylinder near the cylinder head extending through the cylinder wall and water jacket and having its outer part 10 preferably enlarged and screwthreaded as shown. In 55 this opening is secured the charge forming and igniting device shown in detail in Fig. 2, this device comprising an inner part 11 and an outer part or head 12, the outer part or head being provided in its periphery with 60 screwthreads to engage the screwthreads of the outer part 10 of the opening. Through the parts 11 and 12 is formed a central opening or bore 13 forming an oil chamber or receptacle the outer end of which is enlarged 65 and screwthreaded to receive a plug 14.

This plug 14 is provided on one side with a passage 15 for oil leading to the oil chamber or receptacle 13 and on the other side with a passage 16 for water leading to a central opening through the plug in which 70 the valve rod 18 is guided. This valve rod extends a considerable distance above the top of plug 14 and is provided near its upper end with a cross bar 19 between which and the top of the plug is a coiled spring 75 20 which acts to hold the valve rod in raised position. The valve rod extends through the plug 14 and through the center of the oil chamber or receptacle 13 and carries at its lower end a valve 21 which has its seat 22 80 at the lower or inner end of the part 11 of the charge forming device. In this valve rod at a point which, when the valve rod is in raised position, is in line with the inner end of the water inlet passage 16, is formed 85 a recess or pocket 23 adapted to receive and hold a small amount of water to be dropped into the oil chamber or receptacle 13 in any convenient manner as by the descent of the valve rod or otherwise.

90 The lower part 11 of the charge forming device is provided with a series of helically arranged ribs 24 between which are helical spaces 25 the inner walls 26 of which form the walls of the oil chamber or receptacle 95 13 and are made relatively thin so as to quickly transmit heat to the oil in 13, while the ribs 24 are of relatively thick metal so as to hold heat imparted to them and maintain the heat of the oil chamber or receptacle when the air, gases or flame in the spaces 25 are not at their highest heat. Carried by the lower part 11 and inclosing its lower end is a cup or cup shaped disk 27 100 of perforated metal.

105 Into the outer end of the oil inlet passage 15 extends a pipe 28 leading from a supply cup 40 to which oil is supplied by pipe 41 from a force pump 29 the piston 30 of which is held normally in retracted position by 110 spring 31, the piston being forced toward the charge forming device at the proper time by any of the usual means employed in engines of this type for operating the oil feeding pump. The supply cup 40 is provided in one side with an overflow pipe 42 which carries off any excess of oil supplied to the cup by the pump, thus maintaining the oil at a constant level. The cup is of 115 such size and the overflow pipe is placed at such distance above the bottom of the cup that the oil in the cup will be only sufficient to keep the engine in operation for a short time without being replenished by the pump. The feed of the oil to the oil chamber or receptacle is by gravity the oil flowing down the pipe 28 which is preferably provided with a check valve 50 which permits the flow of oil into the oil chamber or receptacle 13 but prevents any forcing of the oil back 120 125 130

into the cup 40 by the pressure in the chamber or receptacle 13. A check valve 32 at the delivery end of the pump serves to prevent any back flow from the cup 40. The pump 5 cylinder is supplied with oil by a pipe 33 leading from any convenient supply, this pipe being provided with a check valve 34.

Into the outer end of the water inlet passage 16 is inserted the end of water supply 10 pipe 35 leading from any convenient water supply such as the water tank 51 shown in dotted lines in Fig. 1.

The valve rod 18, as stated, is held normally raised by spring 20. To cause the 15 valve 21 to be opened and the pocket 23 to carry the water contained in it down into the oil chamber at the proper time, this valve rod is forced downward against the force of the spring. Any convenient means 20 operated from the cam shaft of the engine or otherwise may be used for this purpose. The means shown comprises a bent arm 36 having its free end above and in line with the upper end of the valve rod and pivoted 25 at 37 in a bracket 38 secured to the cylinder or cylinder head, and arranged to be operated by any convenient means from the cam shaft of the engine.

In starting the engine, a supply of fuel 30 oil and water being provided, and the engine cylinder being filled with air, the engine shaft is turned over by hand or by electrically operated or other starting means causing the oil pump to force oil into the 35 cup 40 from which it flows by gravity into the oil chamber or receptacle 13, and also causing the piston to compress the air in the cylinder. As above explained, the piston preferably fits tightly in the cylinder so 40 as to compress the air to a relatively high degree, preferably to 300 pounds to the square inch or more. The highly heated compressed air is forced into the opening 9 and, acting on the thin walls 26 of the oil 45 chamber or receptacle, heats the oil therein, which, as the center of the chamber or receptacle is occupied by the valve rod 18, is in the form of a hollow cylinder having its outer surface exposed to the heated walls, 50 and brings this oil at once to approximately the temperature of the heated air. As the piston reaches the end of its compression stroke the bent arm 36 is operated to force the valve rod downward carrying the water 55 with which the pocket 23 has been filled down into the upper end of the oil chamber or receptacle into the highly heated oil, the water entering the oil chamber or receptacle as water and at normal pressure and being 60 positively carried into it and not forced in by pressure of a pump or other pressure means which might yield to back pressure. The hot oil instantly converts this water 65 into steam at very high temperature and at very high pressure practically causing it to

explode and to force the hot oil out through the discharge port formed at the lower end of the chamber, the valve 21 being opened by the downward movement of the valve rod simultaneously with the introduction of 70 the water into the oil chamber or receptacle. The hot oil is thus forcibly expelled from the oil chamber or receptacle and through the perforations in the cup shaped disk 27 into the hot compressed air in the 75 compression space very much as a charge of shot is expelled from a gun by the explosion of the powder charge, and is finely broken up and scattered through the body of compressed air, the force with which the oil 80 particles are driven through the compressed air or possibly their impact on the heating device of the oil chamber producing an increase of temperature sufficient to effect ignition without the need of special igniting 85 means and without the high compression required in the Diesel type of engine. The first ignition thus produced is sufficient to start the engine into operation.

The first ignition heats up the engine so 90 that on the second compression stroke of the piston the charge of oil introduced into the oil chamber or receptacle from the cup 40 is more quickly and, perhaps, more highly heated. The heating of the second 95 and subsequent charges of oil is further facilitated by the heat of the ignited gases which are forced by the explosion into the helical chamber 25, as described in the patent issued to me December 3, 1901, No. 100 688,245, filling this chamber with unconsumed gases which continue to burn therein, sufficient oxygen to support combustion being supplied by an air inlet duct 43 formed in the outer part 10 of the device, 105 and by their continued combustion as well as by their initial heat heating the walls of the oil chamber or receptacle, the helical ribs 24 holding the heat as the gases begin to lose their heating power, the flame of the 110 combustion of these gases also serving as an additional means for insuring ignition of the second and subsequent charges. The air inlet duct 43 is preferably provided with a check valve 52 so arranged as to permit 115 air to be drawn into the helical chamber 25 on the suction stroke of the piston but to prevent air from passing out through it.

The valve 21 opens outward from the oil chamber or receptacle and the pressure of 120 the air as it is compressed in the compression space tends to hold the valve tightly to its seat against possible entry of air to mix with the oil and cause ignition within the oil chamber. The discharge port formed by 125 the open lower end of the oil chamber or receptacle and controlled as described by the valve 21, is preferably of the full diameter of the chamber so as to form no obstruction to the free discharge of the oil which is thus 130

completely expelled by the explosion of the water leaving nothing in the chamber to form a deposit of carbon or other matter.

I do not herein claim the method of operation carried out by the apparatus herein described, as that forms the subject matter of a separate application for Letters Patent filed by me on the 5th day of February, 1920, No. 356,561.

10 Having thus described my invention what I claim is:—

1. In an internal combustion engine a charge forming device comprising a receptacle adapted to contain oil arranged in position to be subjected to the heat of air compressed in the compression space of the engine having an opening therein for the release of its contents into the compression space and means for closing it against admission of air into the receptacle from the compression space, oil feeding means for introducing oil into the receptacle and means independent of the oil feeding means for introducing a substance expansible by heat 25 into the receptacle after the introduction of the oil thereinto.

2. In an internal combustion engine a charge forming device comprising a receptacle adapted to contain oil arranged in position to be subjected to the heat of air compressed in the compression space of the engine having an opening therein for the release of its contents into the compression space and means for closing it against admission of air into the receptacle from the compression space, oil feeding means for introducing oil into the receptacle and means independent of the oil feeding means for mechanically moving a substance expansible by heat into the receptacle after the introduction of the oil thereinto.

3. In an internal combustion engine a charge forming device comprising a receptacle adapted to contain oil arranged in position to be subjected to the heat of air compressed in the compression space of the engine, means for introducing oil into the receptacle, means for closing the receptacle against the admission of air from the compression space, means for introducing a substance expansible by heat into the receptacle, and means for releasing the contents of the receptacle into the compression space.

4. In an internal combustion engine a charge forming device comprising a receptacle adapted to contain oil arranged in position to be subjected to the heat of air compressed in the compression space of the engine, means for introducing oil into the receptacle, means for closing the receptacle against the admission of air from the compression space, means for introducing a substance expansible by heat into the receptacle and simultaneously releasing the contents of the receptacle into the compression space.

5. In an internal combustion engine a charge forming device comprising a receptacle adapted to contain oil arranged in position to be subjected to the heat of air compressed in the compression space of the engine having an opening therein for the release of its contents into the compression space and means for closing it against admission of air into the receptacle from the compression space, oil feeding means for introducing oil into the receptacle and means independent of the oil feeding means for introducing water into the receptacle after the introduction of the oil thereinto.

6. In an internal combustion engine a charge forming device comprising a receptacle adapted to contain oil arranged in position to be subjected to the heat of air compressed in the compression space of the engine having an opening therein for the release of its contents into the compression space and means for closing it against admission of air into the receptacle from the compression space, oil feeding means for introducing oil into the receptacle and means independent of the oil feeding means for bodily transferring water from outside the receptacle into contact with the oil therein.

7. In an internal combustion engine a charge forming device comprising a receptacle adapted to contain oil arranged in position to be subjected to the heat of air compressed in the compression space of the engine, means for introducing oil into the receptacle, means for closing the receptacle against the admission of air from the compression space, means for introducing water into the receptacle and simultaneously releasing the contents of the receptacle into the compression space.

8. In an internal combustion engine a charge forming device comprising a receptacle adapted to contain oil arranged in position to be subjected to the heat of air compressed in the compression space of the engine, and having a discharge port leading to the compression space and a valve normally closing the discharge port against admission of air from the compression space, means for introducing oil into the receptacle, means for introducing water into the receptacle and simultaneously opening the valve of the discharge port.

9. In an internal combustion engine a charge forming device comprising a receptacle of tubular form adapted to contain oil arranged in position to be subjected to the heat of air compressed in the compression space of the engine, and having a discharge port of the full diameter of the interior of the receptacle leading to the compression space and a valve normally closing the discharge port against admission of air from the compression space, means for introducing oil into the receptacle, and means for

introducing water into the receptacle and simultaneously opening the valve of the discharge port.

10. In an internal combustion engine a charge forming device comprising a receptacle adapted to contain oil arranged in position to be subjected to the heat of air compressed in the compression space of the engine, having a discharge port at its inner 10 end leading to the compression space and means for closing the discharge port against admission of air into the receptacle from the compression space, oil feeding means for introducing oil into the receptacle and means 15 independent of the oil feeding means for introducing water into the receptacle at its outer end.
11. In an internal combustion engine a charge forming device comprising a receptacle adapted to contain oil arranged in position to be subjected to the heat of air compressed in the compression space of the engine, and having a discharge port at its inner end leading to the compression space, 20 and means for closing it against admission of air from the compression space, means for introducing oil into the receptacle, and means for simultaneously introducing water into the receptacle at its outer end and opening the discharge port.
12. In an internal combustion engine a charge forming device comprising a receptacle adapted to contain oil arranged in position to be subjected to the heat of air compressed in the compression space of the engine, and having a discharge port at its inner end leading to the compression space, 25 means for closing the outer end of the receptacle having an opening therethrough for a valve rod, means for introducing oil into the receptacle, a valve rod carrying a valve for closing the discharge port, and means carried by the valve rod for introducing water into the receptacle.
13. In an internal combustion engine a charge forming device comprising a receptacle adapted to contain oil arranged in position to be subjected to the heat of air compressed in the compression space of the engine, and having a discharge port at its inner end leading to the compression space, 30 means for closing the outer end of the receptacle having an opening therethrough for a valve rod, means for introducing oil into the receptacle, a valve rod carrying a valve for closing the discharge port, and means carried by the valve rod for introducing water into the receptacle.
14. In an internal combustion engine a charge forming device comprising a receptacle adapted to contain oil arranged in position to be subjected to the heat of air compressed in the compression space of the engine, and having a discharge port at its inner end leading to the compression space, 35 means for closing the outer end of the receptacle having an opening therethrough for a valve rod, means for introducing oil into the receptacle, a valve rod carrying a valve for closing the discharge port, and means carried by the valve rod for introducing water into the receptacle.
15. In an internal combustion engine a charge forming device comprising a receptacle adapted to contain oil arranged in position to be subjected to the heat of air compressed in the compression space of the engine, and having a discharge port at its inner end leading to the compression space, 40 a plug for closing the outer end of the receptacle having an opening therethrough for a valve rod and a water inlet passage leading to the opening for the valve rod, means for introducing oil into the receptacle, a valve rod carrying a valve for closing the discharge port and extending through the opening in the plug having a pocket formed therein adapted to receive water from the water inlet passage and to carry it into the receptacle.
16. In an internal combustion engine a charge forming device comprising a receptacle adapted to contain oil arranged in position to be subjected to the heat of air compressed in the compression space of the engine, and having a discharge port at its inner end leading to the compression space, 45 means for closing the outer end of the receptacle having an opening therethrough for a valve rod, means for introducing oil into the receptacle, a valve rod carrying a valve for closing the discharge port and extending through the opening in the means for closing the outer end of the receptacle, means carried by the valve rod for introducing water into the receptacle, a spring for holding the valve normally closed and means for operating the valve rod against the force of the spring to cause the discharge port to be 50 opened.
17. In an internal combustion engine a charge forming device comprising a receptacle adapted to contain oil arranged in position to be subjected to the heat of air compressed in the compression space of the engine, and having a discharge port at its inner end leading to the compression space and means for closing it, oil feeding means for introducing oil into the receptacle, means independent of the oil feeding means for introducing water into the receptacle and for opening the discharge port and a perforated disk inclosing the inner end of the receptacle.
18. In an internal combustion engine a charge forming device comprising a receptacle adapted to contain oil arranged in position to be subjected to the heat of air 55

- compressed in the compression space of the engine, having a discharge port at its inner end leading to the compression space and having the wall of its inner portion provided on its exterior with ribs of relatively thick metal, means for introducing oil into the receptacle, and means for introducing water into the receptacle.
19. In an internal combustion engine a charge forming device comprising a receptacle adapted to contain oil arranged in position to be subjected to the heat of air compressed in the compression space of the engine, having a discharge port at its inner end leading to the compression space and having its inner portion provided with ribs of relatively thick metal on the exterior of its walls and with walls of relatively thin metal in the spaces between the ribs, means for introducing oil into the receptacle, and means for introducing water into the receptacle.
20. In an internal combustion engine a charge forming device comprising a receptacle adapted to contain oil arranged to be subjected to the heat of air compressed in the compression space of the engine, having a discharge port at its inner end leading to the compression space and having the wall of its inner portion provided on its exterior with helical ribs of relatively thick metal having spaces between them forming a helical chamber communicating with the compression space, means for introducing oil into the receptacle, and means for introducing water into the receptacle.
21. The combination with an internal combustion engine having an opening in the wall of its compression space of a charge forming device extending into said opening and comprising a receptacle adapted to contain oil, having a discharge port at its inner end and having a part of its inner portion of such exterior diameter as to leave a space between it and the wall of the opening, means for introducing oil into the receptacle, means for holding the discharge port normally closed, and means for introducing water into the receptacle and simultaneously opening the discharge port.
22. The combination with an internal combustion engine having an opening in the wall of its compression space of a charge forming device extending into said opening and comprising a receptacle adapted to contain oil, having a discharge port at its inner end and having a part of its inner portion of such exterior diameter as to leave a space between it and the wall of the opening, and having a disk of perforated metal inclosing its inner end, means for introducing oil into the receptacle, means for holding the discharge port normally closed, and means for introducing water into the receptacle.
23. A charge forming device for internal combustion engines comprising an outer portion and an inner portion having a chamber extending through said outer and inner portions adapted to contain oil, means for closing the outer end of the chamber, a valve for closing the inner end, yielding means for holding the valve normally closed, an oil inlet passage leading to the chamber, and means for introducing water into the chamber.
24. A charge forming device for internal combustion engines comprising an outer portion and an inner portion having a chamber extending through said outer and inner portions adapted to contain oil, means for closing the outer end of the chamber, a valve for closing the inner end, yielding means for holding the valve normally closed, an oil inlet passage leading to the chamber, and means for introducing water into the chamber.
25. A charge forming device for internal combustion engines comprising an outer portion and an inner portion having a chamber extending through said outer and inner portions adapted to contain oil, means for closing the outer end of the chamber, a valve for closing the inner end, means for holding the valve normally closed, a disk of perforated metal extending over and inclosing the inner end of the chamber, an oil inlet passage leading to the chamber, and means for introducing water into the chamber.
26. A charge forming device for internal combustion engines comprising an outer portion and an inner portion having a chamber extending through said outer and inner portions adapted to contain oil, means for closing the outer end of the chamber having an opening therethrough for a valve rod, a valve for closing the inner end of the chamber, a valve rod for said valve extending through the opening in the means for closing the outer end of the chamber, an oil inlet passage leading to the chamber, and means carried by the valve rod for introducing water into the chamber.
27. A charge forming device for internal combustion engines comprising an outer portion and an inner portion having a chamber extending through said outer and inner portions adapted to contain oil, means for closing the outer end of the chamber having an opening therethrough for a valve rod, a valve for closing the inner end of the chamber, a valve rod for said valve extending through the opening in the means for closing the outer end of the chamber, and a pocket carried by the valve rod for introducing water into the chamber.
28. A charge forming device for internal combustion engines comprising an outer portion and an inner portion having a cylindrical chamber extending through said outer and inner portions adapted to contain oil.

having an opening at its inner end of the full diameter of the chamber, a valve for closing said opening, a valve rod for said valve, means for closing the outer end of the chamber having an opening therethrough for said valve rod, and means carried by the valve rod for introducing water into the chamber.

29. A charge forming device for internal combustion engines comprising an outer portion and an inner portion having a chamber extending through said outer and inner portions adapted to contain oil and having its inner end open, a valve for closing the inner end of the chamber, a valve rod for said valve, a plug for closing the outer end of the chamber having an opening therethrough for said valve rod, an oil inlet passage leading to the chamber and a water inlet passage leading to the opening for the valve rod, and a pocket carried by the valve rod for carrying water from the water inlet passage into the chamber.

30. A charge forming device for internal combustion engines comprising an outer portion and an inner portion having a chamber extending through said outer and inner portions adapted to contain oil and having its inner end open, a valve for closing the inner end of the chamber, a valve rod for said

valve, a plug for closing the outer end of the chamber having an opening therethrough for said valve rod, an oil inlet passage leading to the chamber and a water inlet passage leading to the opening for the valve 35 rod, a spring carried by the valve rod outside the plug for holding the valve closed, and a pocket carried by the valve rod for carrying water from the water inlet passage into the chamber.

40

31. A charge forming device for internal combustion engines comprising an outer portion and an inner portion having a chamber extending through said outer and inner portions adapted to contain oil and having its 45 inner end open, a perforated disk extending over and inclosing the inner end of the chamber, a valve for closing the inner end of the chamber, a valve rod for said valve, a plug for closing the outer end of the 50 chamber having an opening therethrough for said valve rod, an oil inlet passage leading to the chamber and a water inlet passage leading to the opening for the valve rod, and a pocket carried by the valve rod 55 for carrying water from the water inlet passage into the chamber.

In testimony whereof I affix my signature this 27th day of January, 1920.

ALBERT HAYES.
